FILE GUIDE

Harry Forsyth, Prosser, Wash.

Application March 18, 1933, Serial No. 661,609

4 Claims. (Cl. 129—29)

This invention relates to file guides and more particularly to an improved means for locking a guide in a file drawer.

An object of this invention is to provide an improved means for releasably locking a file guide at any desired point within the length of the drawer, the locking means being so constructed that it may be readily mounted on any desired type of file guide.

10 Another object of this invention is to provide a guide and locking means therefor which is so constructed that it can be used with any conventional file drawer having a T-shaped channel in the bottom thereof to hold the guides in desired fixed 15 position within the length of the drawer.

The above and various other objects and advantages of this invention will in part be described and in part be understood from the following detailed description of the present preferred embodiment, the same being illustrated in the accompanying drawing wherein:—

Figure 1 is a fragmentary transverse sectional view of a conventional drawer construction having a device constructed according to the preferred embodiment of this invention mounted therein, the device being shown in fragmentary front elevation.

Figure 2 is a sectional view taken on the line 2—2 of Figure 1.

30 Figure 3 is a sectional view taken on the line 3—3 of Figure 2.

Figure 4 is a fragmentary perspective view of a modified form of file guide.

Figure 5 is a similar view of a further type of 35 file guide supporting means.

Referring to the drawing wherein like numerals designate corresponding parts throughout the several views, the numeral 10 designates generally a conventional drawer which is provided with a

40 T-shaped file guide channel 11 in the bottom 13 thereof. This guide channel 11 extends longitudinally of the drawer 10 and is conventional in drawer structures having adjustable file guides positioned therein.

45 In order to provide a means whereby the file guide in the drawer 10 may be releasably locked in any desired position in the length of the drawer 10, I have provided a plate 12 which has integral therewith a U-shaped member 14, being connected 50 to the plate 12 by means of a stem portion 15. This plate 12 is adapted to be secured to a file guide back 16 as by securing members 17 passing through suitable apertures about the surface of the plate 12.

55 An eccentric locking member comprising a

lever 18 pivoted on a pivot 19 is mounted between the parallel legs of the U-shaped member 14. A resilient cam 20 is integral with the lever 18 and is formed by bending a portion of the material of the lever 18 in looped form and mounting this 60 loop or cam 20 in offset relation to the pivot 19. An outwardly extending stop or lug 21 is integral with the upper end of the lever 18, and is adapted to limit the swinging movement of this lever 18 in the U-shaped cross bar portion 14. 65

The bight of the U-shaped member 14 is provided with an opening 22 through which the cam member 20 is adapted to project, and the cam member 20 is adapted to frictionally engage the bottom of the T-shaped guide channel 11 and to 70 force the outer end portions of the U-shaped member 14 which project beyond the opposite edges of the stem or connecting member 15 upwardly against the lower edge of the T-shaped channel 11 and thereby frictionally bind the plate 75 12 with the guide back 16 relative to the guide channel 11.

In Figure 4, the U-shaped lever supporting member 14a is integral with a file guide back 16a which is preferably made of metal and is connected thereto by means of a stem or connecting member 15a of a length less than the length of the member 14a, so that this member 14a may be positioned within the enlarged portion of the 80 guide channel 11. 85

In Figure 5, there is disclosed a further form of this invention wherein the plate 12a is provided with lateral extensions 23 provided with suitable apertures 24 to receive securing members so that the file guide back attached to the plate 12a and the extensions 23 will be held against bending at a point on either side of the guide channel within which the lever supporting member or clamp 14b is positioned. This member 14b is connected to the plate 12a by means of connecting member 15b in a manner similar to the connection of the clamping member 14 to the plate 12. 90 95

In the use of this device, the file guide back 16 may be secured by means of securing members such as rivets, grommets or the like, to the supporting plate 12 and the clamp member 14 may be positioned in the T-shaped channel 11. The lever 18 may be swung to one side into released position, which is shown in dotted lines in Figure 1, and in this position, the eccentric 20 is out 100 of engagement with the bottom of the guide channel 11. When it is desired to releasably lock the file guide back 16 in the drawer 10, the lever 18 can be swung in the opposite direction or into a position similar to that shown in full lines in 110

Figures 1 and 3, and in this position the eccentric 20 will project through the opening 22 and will frictionally engage the bottom of the guide channel 11.

5 It will be obvious from the foregoing that a file guide and locking means therefor has been provided wherein the guide can be released to freely slide to the desired position within the guide channel or may be frictionally locked 10 against movement at any desired point within this channel.

It is, of course, understood that various changes and modifications may be made in the details of construction and design of the above 15 specifically described embodiment of this invention without departing from the spirit thereof, such changes and modifications being restricted only by the scope of the following claims.

What is claimed is:—

20 1. A file guide comprising a plate, a substantially T-shaped member integral with the plate and adapted to engage in a T-shaped guide channel of a file drawer, said T-shaped member including a reverted means extending in a direction 25 parallel to the plate, a rock lever, means for pivotally mounting one end of the lever between said reverted means and the lower portion of the T-shaped member, and an eccentric integral with the lever, said T-shaped member having an 30 opening in the lower portion thereof through which the eccentric is adapted to project upon rocking of the lever in one direction to frictionally bind the plate in a desired position relative to the length of the guide channel.

35 2. A file guide comprising a plate and a file guide back, means for securing the back to the plate, said plate comprising a T-shaped clamping

member having a U-shaped lower portion projecting below the plate and adapted to engage within a T-shaped guide channel of a drawer, a rock lever, means for rockably mounting the lever between the parallel legs of the U-shaped clamping member, said clamping member having an opening in the bight thereof, and a looped spring cam member integral with the lever and adapted to project through the opening of the clamping member upon movement of the lever into operative position.

80 3. A file guide as set forth comprising a plate, a means integral with the plate adapted to engage in a T-shaped guide channel, a rock lever carried by said means, and an eccentric integral with the lever and adapted upon movement of the lever in one direction to project below said means for engagement with the guide channel of a file drawer to frictionally bind said means against the lower surfaces of the parts overhanging the channel.

90 4. A file guide comprising a plate, a U-shaped clamping member supported in depending relation to the plate and adapted to be positioned within the cross bar portion of a T-shaped guide 100 channel and to extend laterally of the narrowest portion of the channel, a lever, means for rockably mounting the lever between the parallel legs of said clamping member, and a resilient cam carried by the lever, said clamping member having an opening through the bight thereof through which said cam is adapted to project to engage the bottom of the T-shaped channel and force the laterally projecting portions of the member against the lower surfaces of the parts overhang- 110 ing the channel.
